(57) **CLAIM**

The ornamental design for a cornhole board, as shown and described.

DESCRIPTION

FIG. 1 is a top, front perspective view of a cornhole board, showing my new design;

FIG. 2 is a bottom, rear perspective view of the cornhole board;

FIG. 3 is a top-down view of the cornhole board;

FIG. 4 is a first side view of the cornhole board;

FIG. 5 is a second side view of the cornhole board;

FIG. 6 is a bottom view of the cornhole board;

FIG. 7 is a rear view of the cornhole board; and,

FIG. 8 is a front view of the cornhole board.

The broken lines in the figures illustrate portions of the article that form no part of the claimed design.
